CONTROL SWITCH

Burton E. Shaw, Bristol, Ind., assignor to Penn Electric Switch Co., Goshen, Ind., a corporation of Iowa

Application May 13, 1940, Serial No. 334,871

8 Claims. (Cl. 200—83)

My present invention relates to a control switch particularly adapted for controlling refrigerant compressor motors in response to changes in pressure, such as those produced by temperature.

One object of the invention is to provide a comparatively simple and efficient switch structure which can be manufactured at low cost and which includes a rugged contact structure and actuating means therefor operable to provide desired snap action for the contacts and at the same time effect their response to the pressure responsive means throughout a comparatively narrow differential of movement thereof.

Another object is to provide a switch structure wherein magnet and armature means effect snap action of a switch arm, the switch arm itself being so connected with a pressure operated actuating arm that the switch contacts are moved slowly toward closed position until the magnet and armature means become effective to quickly snap them the rest of the way to their closed position, operation in the reverse direction, however, permitting the contacts to remain engaged under constraint of at least the magnet and armature means until the toggle spring passes dead center, and thereupon snap action is effected throughout the entire movement of the switch arm from closed to open circuit position.

Another object is to provide a manual control means which is effective to move the switch to "off" position, regardless of the position of the pressure responsive means and the manual control member being very simple and yet efficient in construction.

A further object is to provide a switch structure so designed that ready access to the switch contacts for making the circuit connections is had, and the contacts are so located that they may be readily cleaned or replaced when necessary.

Still a further object is to provide a switch structure in which a simple bracket arrangement permits ready mounting of the various parts of the switch structure thereon and the sub-assembly thus provided is readily mounted within a switch casing.

With these and other objects in view, my invention with respect to its features which I believe to be novel and patentable will be pointed out in the claims appended hereto. For a better detailed understanding of the invention, and further objects relating to details of economy of my invention, reference is made to the following description and to the accompanying drawings 55

wherein such further objects will definitely appear, and in which

5 Figure 1 is a front elevation of a switch structure embodying my invention, the cover part of the casing being shown in section and the switch being shown in open circuit position;

Figure 2 is a vertical sectional view thereof showing the switch about to be closed;

Figure 3 is a similar sectional view showing the 10 switch in its closed circuit position;

Figure 4 is an end elevation from the left end of Figure 1 showing the cover part of the casing in section;

Figure 5 is a similar end elevation of the right 15 hand end of Figure 1;

Figure 6 is a plan view of my control switch, with a cover plate removed and certain parts shown in section, as taken on the line 6—6 of Figure 2;

20 Figure 7 is a horizontal sectional view on the line 7—7 of Figure 2;

Figure 2a is a diagrammatic view of the pivot point relations in Figure 2, and

Figure 3 is a diagrammatic view of the pivot 25 point relations in Figure 3.

On the accompanying drawings I have used the reference character C to indicate generally a casing consisting of back, bottom and top walls 10, 12 and 14, respectively, forming part of the switch 30 casing. A cover portion of the casing has a front wall 15 and end walls 16 and 17. The walls 16 and 17 are held in position by screws 18 entering threaded ears 19 of the back wall 10. The walls 16 and 12 are provided with knockout discs 20 for the purpose of making circuit connections to the switch within the casing C. Within the casing C, I provide a bracket B having a front vertical portion 21, a horizontal shelf 22 and a back vertical portion 23. The lower edge of the portion 21 35 terminates in a pair of feet 24 secured to the casing bottom 12 by screws 25. The portion 23 rests against a boss 26 extending from the back wall 10 and a screw 27 extends from the boss and is threaded into the bracket portion 23. The bracket B further includes an upstanding flange 28 terminating in a flange 29 provided with a pivot opening 30. Complementary to the flange 29 is an extension 31 from the bracket portion 23 having a similar pivot opening 32.

An L-shaped actuating arm A is provided having a horizontal arm 33 and a vertical arm 34. Perforated ears 35 extend from the actuating arm A and are pivoted to a pin 36. The pin 36 is supported by the back wall 10 of the casing C and by the front portion 21 of the bracket B, the

pin being held in position by a retainer clip 37. The right hand end of the arm 33 is bifurcated to coat with stop shoulders 38 and 39 of a stop bracket 40. A pair of washers 41 and 42 are arranged on opposite sides of the arm 33 and are provided with pointed ears 43 and 44, respectively. The ears 43 and 44 are seated in slight depressions in the arm 33 and the washers 41 and 42 are backed by an actuating pin 45 and a range adjusting spring 46, respectively.

The actuating pin 45, as shown in Figure 2, is connected to the head 47 of a bellows 48. The bellows 48 is located in a bellows chamber 49 from which a capillary tube 50 extends to a capillary bulb or coil 51. The bellows and capillary tube 15 and bulb system may be suitably charged in the usual manner for varying the pressure within the bellows chamber 49 against the head 47 of the bellows 48, in response to temperature changes in the temperature range for which the switch is 20 designed.

The range adjusting spring 46 has its upper end engaging with an adjusting washer 52 into which is threaded an adjusting rod 53. The washer 52 has an extension 54 into a slot 55 of the bracket B to prevent rotation of the washer but permit axial movement thereof relative to the adjusting rod. The adjusting rod is rotatable in the shelf 22 of the bracket and in the top wall 14 of the casing C. A control knob 56 is secured 25 to the outer end of the adjusting rod and may coat with suitable indicia on a cover plate 57 indicating the temperature settings in the usual manner.

A switch arm S is provided having a pair of 35 pivot extensions 58 and 59 entering the pivot openings 30 and 32, respectively, of the bracket B. For operating the switch arm S from the actuating arm A, I provide a pair of spring cups 60 and 61 pivotally engaging an extension 62 of the 40 switch arm S and the upper end of the vertical arm 34 of the actuating arm A. A toggle or over-center spring 63 is interposed between the spring cups 60 and 61.

The arm 34 of the actuating arm A has secured thereto a leaf spring 64 which may be adjusted relative to the arm 34 by a set screw 65. The spring 64 is adapted at times to engage an extension 66 from the shelf 22 of the bracket B.

The switch arm S has a downward extension 67 terminating in a finger 68 located under the spring cup 61. An armature 69 is carried by the switch arm S and is adjustable relative thereto by reason of being secured to a rod 70 threaded in the switch arm.

The switch arm S carries a bridging contact member 71 having a pair of upstanding ends 72. The ends 72 are freely slideable through openings 73 in an insulating member 14 of the switch arm S. The bridging member 71 is urged downwardly by a leaf spring 75 arranged below the switch arm member 74 and having its ends located in slots 76 of the upstanding member 72. A retainer clip 77 limits the bridging member 71 in its downward movement relative to the arm 14.

The bridging member 71 carries a pair of contacts 78 adapted to bridge a pair of stationary terminals 79. The terminals 79 are mounted in a block 80 of insulating material and are provided with terminal screws 81 for making circuit connections. The block 80 is secured to the shelf 22 of the bracket B as by a screw 82.

A permanent horseshoe magnet 83 is mounted on the block 80 by means of a screw 84. The

70 magnet 83 coacts with the armature 69 for securing snap action, as will hereinafter appear.

In the top 14 of the casing C below the cover plate 57, an elongated depression 85 is provided. A slide bar 86 is slideable therein and is retained therein by the cover plate. The slide bar 86 has one end downturned as at 87, which end passes through a slot 88 in the top wall 14 of the casing. The other end is upturned as at 89 and passes through a slot 90 in the cover plate 57. The downturned end 87 enters a slot 91 of the switch arm S, while the upturned end 89 is provided for convenience in manual manipulation of the slide bar 86.

A spring wire catch 92 is provided to retain the slide bar 86 in one of two adjusted positions. The spring 92 coacts with either a pair of notches 93 or a pair of notches 94 in the bar 86, as shown in Figure 6, for this purpose. The spring catch is retained in its proper position in the depression 85 by the cover plate 57 and is retained against longitudinal sliding movement with the bar 86 by certain portions thereof projecting into a slot 95 of the casing C, as shown in Figure 2.

Practical operation

In the operation of my switch structure in response to pressure changes in the bellows chamber 49, a relatively low pressure condition in the chamber will permit the parts to assume open circuit position, as illustrated in Figure 1. Upon a rise of pressure, the arm 34 of the actuating arm A will move from the position of Figure 1 (with the pivot points 34 and 62 aligned indicated by the center line 96a and such center line falling to the right of the pivot point 58) toward the position of Figure 3. When the pivot points at the upper end of the arm 34 reach a position substantially in alignment with the pivot points of the elements 58 and 59, taken with relation to the pivot point of the element 62, the switch arm S will start moving in synchronism with the arm A until approximately the position of Figures 2 and 2a is reached. The pivot points of the elements 34, 58, 59 and 62 are still substantially in alignment, as indicated by the center line 96. The armature 69 is now sufficiently close to the magnet 83 for the magnet to exert enough pull on the armature to swing the toggle spring 63 on past dead center, so that the switch closes to the position of Figures 3 and 3a with snap action and the actuating arm A may move on from the position of Figures 2 and 2a (dotted position of Figures 3 and 3a) to the full line position of Figures 3 and 3a (on center line 97), as a result of overrun causing further pressure increase in the bellows chamber 49.

Slow movement of the switch to position with the contacts adjacent each other, as in Figures 2 and 2a, insures the elimination of any bouncing of the contacts when the switch closes. The remaining distance is so short and since the pull of the magnet on the armature increases in proportion to the square of the distance of travel, that movement from the Figures 2 and 2a position to the Figures 3 and 3a position produces a positive closing of the contacts without bouncing. Thus I eliminate the undesirable arcing experienced with some switches upon closure.

When the pressure in the bellows chamber 49 recedes, the range spring 46 will cause the bellows to expand and the actuating arm to move reversely from the full line position of Figures 3 and 3a to the dotted line position. The respective center lines are indicated at 97 and 96, and

when the center line 96 is reached the toggle spring connection passes dead center, so that it immediately urges the switch arm S toward open circuit position. When the parts are in the full line position of Figures 3 and 3a, the switch contacts are held in engagement by the action of the magnet and armature in addition to the tension in the toggle spring. The toggle spring tension reduces to zero at center line 96, but the contacts are still held firmly in engagement with each other by the action of the magnet and armature. After the dead center position, the contacts are quickly separated and it is evident from such an arrangement as above described that there is no gradual reduction of contact pressure to zero, as in usual toggle spring connections of switch structures. There is always a minimum contact pressure produced by the magnet and armature, and this pressure is instantly relieved when the toggle spring passes dead center and acts in conjunction with the armature and magnet to effect quick movement of the switch arm from closed circuit to open circuit position throughout its entire travel.

When the slide bar 86 is in the position of Figures 2 and 3, the switch will operate automatically in the normal manner. If the slide bar 86 is moved to the left, so that the spring catch 92 coacts with the notches 94, then the projection 87 of the slide bar swings the switch arm clockwise to the open circuit position of Figure 1, even though the pressure responsive means is calling for a closed circuit condition.

The particular arrangement of armature and magnet cooperating with the toggle spring as I have disclosed produces the desired contact action above described, and does so with a minimum of parts for the manufacture of the switch. The terminals 79 are conveniently located for ready access for wiring purposes and for renewal and cleaning of the contacts of the switch when necessary. The arrangement of parts is also such that the time required for assembly is reduced to a minimum, and all of these features contribute to the production of an economical switch structure which operates efficiently and will give exceptional service.

I have illustrated and described my improvement in an embodiment which I have found very satisfactory. I have not attempted to illustrate or describe certain adaptations or modifications which I contemplate, or the various uses and adjustments possible, as it is believed that the foregoing disclosure will enable those skilled in the art to which this invention appertains to embody or adapt my improvements as may be desired.

Having thus described my invention, I now claim and desire to secure by Letters Patent:

1. In a control switch, pressure responsive means, an actuating arm movable in response thereto, a pivoted switch arm, switch contacts controlled thereby, an armature carried by said switch arm, a stationary magnet cooperating with said armature to impart snap action to said switch arm, an operative connection between said switch arm and said actuating arm comprising a toggle spring having its ends pivoted to said switch arm and actuating arm with the main pivot of the switch arm located intermediate the pivots of said toggle spring to said arms, said toggle spring thereby effecting slow movement of said switch arm toward closed position until said contacts are closely spaced and said armature and magnet means have approached a point permitting said magnet to attract said arma-

ture and thereby finish the contact closing operation with snap action and said toggle spring, in response to reverse action of said pressure responsive means, effecting build-up of tension therein to a point where, when the toggle spring passes dead center, it will overcome the pull of the magnet on the armature and effect snap action throughout the complete movement of said switch arm from closed to open position.

2. In a control switch, pressure responsive means, an actuating arm movable in response thereto, a switch arm, switch contacts controlled thereby, an armature carried by said switch arm, a stationary magnet cooperating with said armature to impart snap action to said switch arm, an operative connection between said switch arm and said actuating arm comprising an overcenter spring, said switch arm being pivoted at a point intermediate the ends of said spring to effect slow movement of said switch arm toward closed position until said contacts are closely spaced, said magnet thereafter attracting said armature to finish the contact closing operation with snap action of said spring as it passes over center in conjunction with said magnet and armature, and said spring, upon passing dead center in response to reverse action of said pressure responsive means, overcoming the pull of said magnet on said armature and snapping said switch arm from closed to open position.

3. In a switch of the character described, pressure responsive means, a pivoted switch arm, switch contacts controlled thereby, an armature carried by said switch arm, a stationary magnet cooperating therewith to impart snap action to said switch arm, and an operative connection between said switch arm and said pressure responsive means including a toggle spring having substantially its central portion aligned with the pivot for said switch arm.

4. In a control switch, a housing, a bracket therein, actuating and switch arms pivoted to said bracket, contacts carried by said switch arm, stationary contacts for cooperation therewith, mounting means for said stationary contacts and mounted on said bracket, a magnet carried by said mounting means, an armature carried by said switch arm to provide snap action for the operation of the switch arm, a toggle spring interposed between said actuating and switch arms, and a leaf spring secured to said actuating arm and engageable with said bracket in the closed circuit position of said actuating arm, said leaf spring being adjustable relative to said actuating arm.

5. In a control switch, a housing, a bracket therein, actuating and switch arms pivoted to said bracket, a contact carried by said switch arm, a stationary contact for cooperation therewith, mounting means for said stationary contact and mounted on said bracket, a magnet, an armature carried by said switch arm and cooperating with said magnet to provide snap action for the operation of the switch arm, a toggle spring interposed between said actuating and switch arms, and a leaf spring secured to said actuating arm and engageable with said bracket in the closed circuit position of said actuating arm.

6. In a control switch, a casing, pressure responsive means, an actuating arm movable in response thereto, a switch arm, switch contacts controlled thereby, armature and magnet means to impart snap action to said switch arm, an operative connection between said switch arm and said actuating arm comprising a toggle

spring, and a manual control for said switch arm comprising a member movable to move said switch arm to open circuit position against the constraint of said toggle spring and magnet and armature means in one position of the member, and to permit free action of the switch arm in the other position of the member, said casing being provided with an elongated depression in which said member is slid able, and a cover for said depression and effective to retain said member therein.

7. In a control switch, pressure responsive means, an actuating arm movable in response thereto, a switch arm, switch contacts controlled thereby, armature and magnet means to impart snap action to said switch arm, an operative connection between said switch arm and said actuating arm comprising a toggle spring, and a manual control for said switch arm comprising a member movable to move said switch arm to open circuit position against the constraint of said toggle spring and magnet and armature means in one position of the member, said member having a pair of notches therein, and a latch

wire engageable selectively with said notches to retain said member in either of its positions.

8. In a control switch, a casing, pressure responsive means, a switch arm, switch contacts controlled thereby, armature and magnet means to impart snap action to said switch arm, an operative connection between said pressure responsive means and said switch arm comprising a toggle spring, and a manual control for said switch arm comprising a member movable to move said switch arm to open circuit position against the constraint of said toggle spring and magnet and armature means in one position of the member, and to permit free action of the switch arm in the other position of the member, said casing being provided with an elongated depression in which said member is slid able, said member having a pair of notches therein, a latch wire engageable selectively with said notches to retain said member in either of its positions, and a cover plate for said casing and retaining said member in said depression.

BURTON E. SHAW.
